UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,615, dated October 3, 1899.

Application filed September 5, 1899. Serial No. 729,565. Term of patent 14 years.

To all whom it may concern:

Be it known that I, JEREMIAH A. SCRIVEN, a citizen of the United States, residing in the borough of Manhattan, city, county, and State of New York, (my post-office address being No. 18 East Fifteenth street, in said city,) have invented and produced a new and original Design for Bifurcated Nether Garments, of which the following is a specification.

10 The essential characteristics of my design consist in a bifurcated panel in the front of the garment, which panel extends in a continuous length from the lower portion of the tubular members of the garment throughout the body portion thereof to substantially the upper end of the garment, the wales of the panel running continuously in a longitudinal direction throughout the length thereof.

In the accompanying drawing the figure 20 represents a front view of a bifurcated nether garment embodying my design.

In the drawing, A indicates the front of the body portion of a nether garment, from

which extend the tubular members B. Let into the front portion of the garment is a bifurcated insertion or panel, which comprises the portion c, bifurcated at its upper end, as indicated at c^x, and which extends substantially throughout the body portion of the garment. This panel likewise has extensions 30 c', which run substantially throughout the length of the tubular members B and which are continuous with the portions c. From the drawing it will be observed that the wales or ribs d of the panel are continuous and extend longitudinally throughout the length of the panel and to substantially the upper end of the garment.

What I claim is—

The design for a bifurcated nether garment 40 substantially as herein shown and described.

JEREMIAH A. SCRIVEN.
